[57] CLAIM

The ornamental design for a barbecue grill lid support device, as shown and described.

DESCRIPTION

FIG. 1 is a left side elevational view of a barbecue grill lid support device showing my new design;

FIG. 2 is a right side elevational view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a top, front, right side perspective view thereof.

The barbecue grill shown in broken lines in figure 7 is for illustrative purposes only and forms no part of the claimed design.
